US00D47511S

(12) **United States Design Patent** (10) Patent No.: **US D475,111 S**
Bennett (45) Date of Patent: **** May 27, 2003**

(54) **SKATE UPPER FOR AN IN-LINE SKATE**

FR 2 668 072 4/1992

(75) Inventor: **D. Paul Bennett**, Seattle, WA (US)**OTHER PUBLICATIONS**(73) Assignee: **K-2 Corporation**, Vashon, WA (US)

“Extremely Different: K2 Exotech,” K2 Corporation brochure, 1993.

(**) Term: **14 Years**

“Extremely Different: K2 Exotech, K2 Exotech Collection,” K2 Corporation advertising copy, 1993.

(21) Appl. No.: **29/153,236**

“Extremely Different: K2 Exotech—The Next Generation,” K2 Corporation advertising copy, date prior to Jun. 20, 1997.

(22) Filed: **Jan. 3, 2002***K2 Graphite Composite Skates Catalog—Men's/Women's*, K2 Corporation, date prior to Jun. 20, 1997.(51) LOC (7) Cl. **21-02**

“K2 Soft Boot Skates: K2 Exotech™ In-Line Skates,” K2 Corporation brochure, 1996.

(52) U.S. Cl. **D21/764**
